[57] CLAIM

The ornamental design for a coupon holder for a shopping cart, as shown and described.

DESCRIPTION

FIG. 1 is a front perspective view of a coupon holder for a shopping cart showing my new design;
FIG. 2 is a front elevational view thereof;
FIG. 3 is a rear elevational view thereof;
FIG. 4 is a side elevational view thereof, the opposite side elevational view being a mirror image of that shown;
FIG. 5 is a top plan view thereof; and,
FIG. 6 is a bottom plan view thereof.

FIG. 1

FIG. 4
